UNITED STATES PATENT OFFICE.

CHARLES A. McDONALD, OF SAN FRANCISCO, CALIFORNIA.

DESIGN FOR A NECKLACE.

No. 39,136.

Specification for Design.

Patented Feb. 18, 1908.

Application filed November 5, 1907. Serial No. 400,891. Term of patent 3½ years.

To all whom it may concern:

Be it known that I, CHARLES A. McDONALD, residing in the city and county of San Francisco, and State of California, have invented a new, original, and ornamental Design for Necklaces, of which the following is a specification, reference being had to the accompanying drawing, forming part thereof.

The figure is a plan view of a necklace, showing my new design.

I claim:
The ornamental design for a necklace, as shown.

CHARLES A. McDONALD.
